Primary Examiner — Cathron Brooks*Assistant Examiner* — Cary M Robinson(74) *Attorney, Agent, or Firm* — McAndrews Held & Malloy, Ltd.(57) **CLAIM**

The ornamental design for a display screen or portion thereof with an icon, as shown and described.

DESCRIPTION

FIG. 1 is a front view of a display screen or portion thereof with an icon showing my new design; and, FIG. 2 is an enlarged view of the ICON of FIG. 1, shown separately for completeness of illustration.

The broken lines in FIG. 1 illustrate a display screen or portion thereof and form no part of the claimed design.
